UNITED STATES PATENT OFFICE.

RUDOLPH HOFFMAN, OF CLEVELAND, OHIO.

OIL STOVE.

Application filed November 30, 1925. Serial No. 72,297.

This invention relates to oil burners and more especially to the type of burner that is commonly known as wickless in which there is an annular fuel well having an asbestos 5 ring, the well being raised or lowered, to change the level of the oil therein in accordance with whether it is desired to have the burner lighted or not.

It is one of the objects of the invention to 10 provide an improved mechanism for supporting and raising and lowering the well and also to provide convenient means whereby the fuel supply passages may be readily cleaned.

15 Other objects of the invention and the features of novelty will be apparent from the following description taken in connection with the accompanying drawings, of which:

20 Fig. 1 is a longitudinal section through a burner embodying my invention, certain parts being shown in side elevation; and

Fig. 2 is a transverse section on the line 2—2 of Fig. 1.

25 Referring to the drawings, 10 indicates an annular well in which there is arranged an asbestos ring 11, the upper edges of the well being provided with flanges 12 and 13 on which the chimney 14 is supported. The 30 lower edge of the well 10 is closed by a wall 15 which is usually made integral with the side walls of the well, the well being preferably stamped out of sheet metal.

Extending across the bottom of the well 35 10, is a tubular support 16 which is secured to the wall 15 at the diametrically opposite points 17 and 18, by welding, brazing or in any other suitable manner. One end of the tubular member 16 is preferably flattened 40 and closed by welding or in any other suitable manner as indicated at 19. The other end of the member 16 is inclined upwardly, adjacent the outer side of the well 10, as indicated at 20, and is provided with a removable closure 21, which may be in the 45 form of a screw or any other preferred type. The upper end of the extension 20 is above the highest level to which the oil rises in the well 10 so that there will be no possibility of the oil overflowing from this extension. A port 22 is provided for the purpose of supplying oil from the member 16 to the interior of the well 10.

50 A vertically extending pipe 23 is welded or otherwise secured to the lower side of the tubular member 16 and slidably ar-

ranged in a supply pipe 24, a stuffing box 25 being provided at the upper end of the pipe 24 for the purpose of preventing leakage of oil. A vertically arranged rack 26 60 is welded or brazed to the flattened portion 27, of the tubular member 16, and extends into a guiding frame 28 which is secured to the pipe 24 and to the horizontal header 29, on which the pipe 24 is mounted. The 65 frame 28 carries a shaft 30 on which there is a sector gear 31, which meshes with the rack 26 so that the rack, together with the well 10 and the chimney 14, may be raised and lowered at will, by rotating the shaft 70 30. The rack 26 also serves as a guide which assists in maintaining the well 10 and the parts, associated therewith, in their proper positions.

The extension 20 provides a convenient 75 means by which the fuel supply passages may be cleaned. For this purpose, it is only necessary to remove the closure member 21 and insert a wire into the extension 20. When the ring 11 is removed from the well, the port 22 is also accessible for cleaning and any foreign material found in the fuel supply passages may be removed through the extension 20.

Having thus described my invention, 85 what I claim is:

1. In burners, an annular well, a tubular member secured to the bottom of said well and extending across the same and provided with an upwardly inclined extension at one 90 side of the well, a supply pipe secured to said member and having communication with the interior of the well through said member, said member being flattened between the sides of said well, and a guiding 95 and lifting member secured to said flattened portion.

2. In burners, an annular well, a tubular member secured to the bottom of said well and extending across the same and provided 100 with an upwardly inclined extension at one side of the well, projecting above the level to which the fuel rises in said well, a vertical supply pipe secured to said member and having communication with the interior 105 of the well through said member, said member having a flattened portion between the sides of said well, and a vertically extending rack secured to said flattened portion.

3. In burners, an annular well, a tubular member secured to the bottom of said well and extending across the same and having 110

communication with the interior of the well for supplying fuel thereto, a vertical supply pipe secured to said member and having communication with the interior thereof, 5 said member having a flattened portion between the sides of said well, and a vertically extending rack secured to said flattened portion.

4. In burners, an annular well, a tubular member secured to the bottom of said well and extending across the same and having communication with the interior of the well 10

for supplying fuel thereto, a vertical pipe secured to said member and having communication with the interior thereof, a supply pipe with which said vertical pipe has telescopic connection, said member having a flattened portion between the sides of said well, a rack secured to said flattened portion of said member, and a guide for said 15 rack secured to said vertical supply pipe.

In testimony whereof, I hereunto affix my signature.

RUDOLPH HOFFMAN.
